UNITED STATES PATENT OFFICE

WILLIAM WILSON, OF NEW YORK, N. Y.

HOUSE-BOAT CONSTRUCTION

Application filed September 9, 1930. Serial No. 480,737.

This invention relates broadly to water-craft, and refers more particularly to an improved house-boat construction, which may be of the type which is either adapted to be towed or self-propelled.

6 The present invention has to do more especially with and comprehends an improved hull and deck structure which is of a built up sectional type, whereby the size thereof can be varied and whereby renewal of the sections or repair thereto in event of damage may be accomplished with the greatest facility.

15 The invention further aims to provide in a house-boat construction, a plurality of independent hulls arranged in parallel relation to respectively make for a better control of the craft, especially where the same is equipped with self-propelling means, to increase its seaworthiness while reducing to an appreciable extent, expense of production of the hull and deck structure.

20 The invention furthermore contemplates in a house-boat construction having a plurality of parallel hulls, a rigid, effectual and lasting means for joining the same together so as to withstand the strains and stresses to which it would ordinarily be subjected.

25 As a still further object, the invention resides in a novel and effectual means for connecting the hull sections so as to insure against accidental disconnection thereof while permitting of ready intentional removal and replacement when necessary.

30 Other objects of the invention reside in the comparative simplicity of construction of the hull and deck structures, the economy with which they may be produced and the general efficiency derived therefrom.

35 With the above recited and other objects in view, reference is had to the following description and accompanying drawings, in which there is exhibited one example or embodiment of the invention, while the claims define the actual scope of the same.

40 In the drawings:

Figure 1 is a side view of a house-boat constructed in accordance with the invention.

45 Figure 2 is a plan view of the deck supporting and hull structures, with the deck and cabin removed.

Figure 3 is a fragmentary enlarged sectional plan view.

Figure 4 is a transverse sectional view therethrough taken approximately on the line indicated at 4—4 in Figure 3.

55 Figure 5 is a fragmentary perspective view.

Figure 6 is a fragmentary longitudinal sectional view.

Figure 7 is a perspective view of one of the end elements of the hull section connecting 60 means.

Figure 8 is a perspective view of one of the cable covering and protecting elements.

Referring to the drawings by characters of reference, A designates generally the complete hulls, a plurality of which are employed, the same being arranged in parallel side by side relation and joined together by a framework B, which also serves to support the deck, as well as the cabin C. The hulls A 65 include bow and stern sections 10 which are identical, and a plurality of identical intermediate sections 11, all of which sections 10 and 11 are of hollow water-tight construction and which combine to produce the necessary 70 displacement and buoyancy to float the craft.

The bow and stern sections 10 of the hull are shaped in such a manner as to offer a minimum of head resistance, being rounded at the outer ends 12 and provided with a continuous 75 groove 13 which extends centrally along the bottom and upwardly throughout the rounded outer ends to the top of said hull section. The sides of the bow and stern sections, as well as the intermediate sections 80

11, are formed with mating grooves 14 adjacent the upper surface of the hull. Nosing pieces 15 are provided for the bow and stern sections 10 to fit around the curved outer ends 85

12 thereof and to extend under the bottom medial portion, and said nosing pieces are provided with ribs 16 which fit within the groove 13. The nosing pieces 15 are also provided with inwardly extending divergent 90

arms 17 having ribs 18 on their inner sides 95 which fit within the grooves 14, and said nosing pieces are formed with upper extremities 19 projecting above the upper surface of the hull. The extremities 19 are each provided with an inwardly projecting apertured ear 100

20. The nosing pieces 15 are each provided with an aperture or tunnel 21 extending throughout the length and terminating in an enlarged bore 22 disposed vertically in the extremity 19, the said enlarged bore having a further enlarged mouth 23 presenting an internal annular shoulder 24. A cable 25 is trained through the apertures 21 of the nosing pieces 15 and is formed with threaded opposite terminals 26 which are engaged by an internally threaded tubular nut 27 lying within the enlarged bore 22 and having a head 28 disposed within the mouth 23 and abutting against the internal shoulder 24. An externally disposed tool engaging portion 29 serves as a means for rotating the nut to exert a longitudinal tension on the cable 25 for binding the hull sections 10 and 11 together. The portions of the cable 25 extending between the lower inner ends of the nosing pieces 15 are covered and protected by the tubular elements 30 having longitudinal apertures or bores 31 and provided with longitudinal ribs 32 which fit within the transverse central grooves 33 on the under side of the intermediate hull sections 11. A pair of cable sections 35 are respectively connected to the apertured ears 20 of the terminals 19 and a turnbuckle 36 connects the inner ends of said cable sections which overlie the upper surface of the hull and by virtue of which a longitudinal tension may be exerted to bind the nosing piece terminals 19 together for drawing the hull sections 10 and 11 in close proximity to each other.

40. The arms 17 are provided with longitudinal apertures or bores 37, through which side cables 38 are trained, having threaded projecting terminals 39 with which nuts 40 are engaged to exert a longitudinal tension on the side cables 38 to bind the hull sections together against lateral relative movement. Cable covering and protecting elements 30 are arranged over the portions of the cables 38 which are disposed between the inner ends of the arms 17 of the opposite nosing pieces. The ribs 32 of the elements 30 snugly fit into the grooves 14 of the hull sections 10 and 11.

50. In order to further brace the sections of the hull structure and to maintain them against vertical or lateral shifting movement, each of the intermediate hull sections is recessed at its opposite ends as at 41, while the bow and stern sections 10 are similarly recessed at the inner ends as at 42. Within the mating recessed ends 41 of the intermediate sections and the recessed ends 42 of the bow and stern sections, there are fitted bridge plates 43, the marginal flanges 44 of which snugly interfit the recessed portions 41 and 42. Obviously, the bridge plates 43 may be lightened by cut-away portions 45, which also facilitate the handling of the bridge plates when installing or removing them from the recessed ends. From the

foregoing, it will be seen that the sectional hull structures may be built up to any desired length and when thus assembled, a damaged section may be repaired or renewed readily.

70. If desired, the hull sections may be filled with air or water-tight members 46 which are introduced through a manhole 47 in the upper wall of the hull sections, a removable cover 48 being provided for the purpose.

75. The framework B for joining two or more of the hull sections together in parallel side by side relation and for supporting the cabin C and the decking D, essentially consists of a pair of keel strips 50 for each hull structure, which keel strips are of an appropriate length to extend throughout the length of the hull structures. The keel strips 50 are joined to each other, and the pairs of keel strips are connected together by cross bars 51 which overlie the same and are mortised therein and which are joined together by vertical bolts 52. Between each pair of hulls, the cross bars 51 have installed a subterposed cross bar section 53 connected thereto by vertical studs 54. The side flanges 56 of transverse channel members are installed alongside of each of the cross bars 51 and are provided with an intermediate drop portion 57, within which the studs and subterposed portion 53 are arranged. Baffle members 58 are secured to the outside of the studs 54 and extend throughout the length of the craft, while baffle slats 59 are secured to the under side of the subterposed cross bar sections 53, and the same function to baffle the waves and protect the floor of the cabin C at the point lying between the hull sections. The keel strips 50 may be secured in any desired manner to the upper side of the hulls, but, preferably, said keel strips are received and embraced by channel sections 60 which are welded, riveted, bolted or otherwise secured to the upper surface of the hulls. After the keel strips are positioned within the channel sections 60, transverse bolts 61 extend through the keel strips and channel sections. The transverse channel members at their outer ends are provided with angularly bent apertured terminals 65, to which are bolted or otherwise secured the gunwale strips 66, over the outer side of which finishing strips 67 may be nailed. The decking D is preferably composed of spaced slats 68, by virtue of which water may drain from the decking.

90. 95. 100. 105. 110. 115. 120. 125. 130. From the foregoing, it will thus be seen that a house-boat hull and deck construction has been devised which is so constructed as to permit of the building of the same in various lengths and widths according to the desires of the individual. The deck and cabin supporting framework, as well as the hulls, is fabricated of sections which not

only facilitate the initial building of the craft but permit of inexpensive repair to or replacement of the parts in event of damage.

- 5 While there has been illustrated and described a preferred embodiment of the invention, it is to be clearly understood that no limitation is necessarily made to the precise structural details herein exhibited, but 10 variations and modifications thereof which fall within the scope of the appended claims may be resorted to when desired.

What is claimed is:

1. In a watercraft, transversely spaced 15 parallel hulls including longitudinally fabricated hull sections, a deck and cabin supporting frame work overlying and joining the hulls including continuous longitudinal keel strips secured to the hull sections and 20 serving to connect the same against longitudinal or vertical separation.

2. In a watercraft, transversely spaced 25 parallel hulls including longitudinally fabricated hull sections having tensioned means for binding the same together and a deck and cabin supporting framework overlying and joining the hulls and including continuous longitudinal keel strips secured to the hull sections and 30 serving to further join the same against longitudinal or vertical separation.

3. A hull construction for watercraft including separate water-tight bow, stern and intermediate sections, the bow and stern sections having recessed inner ends and the intermediate sections having recessed opposite ends, bridge members respectively fitted in the recessed ends of adjacent sections and tensioned means for longitudinally binding the sections together.

40 4. A watercraft including transversely spaced parallel hulls each composed of a plurality of longitudinal sections having mating recessed ends, bridge elements respectively fitted in the recessed ends of adjacent 45 sections and tensioned means for binding the sections together.

5. A watercraft including transversely spaced parallel hulls each composed of a plurality of longitudinal sections having mating recessed ends, bridge elements respectively fitted in the recessed ends of adjacent sections and exteriorly disposed tensioned means for binding the sections together.

6. A watercraft including transversely 55 spaced parallel hulls each composed of a plurality of longitudinal sections having mating recessed ends, bridge elements respectively fitted in the recessed ends of adjacent sections, exteriorly disposed tensioned means 60 for binding the sections together and a deck and cabin supporting framework connecting the hulls in their spaced parallel relation.

7. A watercraft including transversely 65 spaced parallel hulls each composed of a plurality of longitudinal sections having mat-

ing recessed ends, bridge elements respectively fitted in the recessed ends of adjacent sections, exteriorly disposed tensioned means for binding the sections together and a deck and cabin supporting framework connecting the hulls in their spaced parallel relation and including continuous longitudinal keel strips serving to further secure the hull sections together.

8. A watercraft including transversely spaced parallel hulls each composed of a plurality of longitudinal sections having mating recessed ends, bridge elements respectively fitted in the recessed ends of adjacent sections, exteriorly disposed tensioned means for binding the sections together and a deck and cabin supporting framework connecting the hulls in their spaced parallel relation and including continuous longitudinal keel strips serving to further secure the hull sections together, the said hull sections having longitudinally extending channel members on their upper sides embracingly receiving the keel strips.

9. A hull construction for watercraft including separate water-tight bow, stern and intermediate sections and means for removably securing said sections in assembled relation consisting of mating grooved portions of said sections and tensioned cables arranged in said grooved portions and traversing the assembled hulls lengthwise.

10. A hull construction for watercraft including separate water-tight bow, stern and intermediate sections, means for removably securing said sections in assembled relation consisting of mating grooved portions of said sections and tensioned cables arranged in said grooved portions and traversing the assembled hulls lengthwise and means receiving the ends of said cables for tensioning the same longitudinally.

11. A hull construction for watercraft including separate water-tight bow, stern and intermediate sections, means for removably securing said sections in assembled relation consisting of mating grooved portions of said sections and tensioned cables arranged in said grooved portions and traversing the assembled hulls lengthwise and cable covering and protecting elements through which the cables extend.

12. A hull construction for watercraft including separate water-tight bow, stern and intermediate sections, means for removably securing said sections in assembled relation consisting of mating grooved portions of said sections and tensioned cables arranged in said sections and traversing the assembled hulls lengthwise and cable covering and protecting elements through which the cables extend, said elements having ribs seated in the hull groove.

13. A hull construction for watercraft including separate water-tight bow, stern and

intermediate sections, means for removably securing said sections in assembled relation consisting of mating grooved portions of said sections and tensioned cables arranged in said sections and traversing the assembled hulls lengthwise and cable covering and protecting elements through which the cables extend, said elements having ribs seated in the hull groove, the end elements including integral portions providing a nosing extending around the transverse center of the bottom and the outer edges of the bow and stern sections.

14. A hull construction for watercraft including separate water-tight bow, stern and intermediate sections, means for removably securing said sections in assembled relation consisting of mating grooved portions of said sections and tensioned cables arranged in said sections and traversing the assembled hulls lengthwise, cable covering and protecting elements through which the cables extend, said elements having ribs seated in the hull groove, the end elements including integral portions providing a nosing extending around the transverse center of the bottom and the outer edges of the bow and stern sections and side arms embracing the grooved upper sides thereof.

15. Signed at New York city in the county of New York and State of New York this 6th day of September 1930.

WILLIAM WILSON.
